United States Patent Office

Des. 186,056
Patented Sept. 1, 1959

186,056

SCREEN AND SOUND ATTACHÉ CASE

John C. Nemesnyik, Nutley, N.J., and Roger W. Wade,
Port Washington, N.Y., assignors to Charles Beseler
Company, East Orange, N.J., a partnership

Application March 27, 1959, Serial No. 55,209

Term of patent 14 years

(Cl. D61—1)

The single figure is a perspective view of a screen and sound attaché case showing our new design, the opposite side and bottom, not shown, having substantially the same appearance as the side and top shown, and the back being conventional.

We claim:

The ornamental design for a screen and sound attaché case, as shown and described.

References Cited in the file of this patent

UNITED STATES PATENTS

D. 151,474	Stern	Oct. 19, 1948
D. 167,363	Peters	July 29, 1952
D. 169,369	Forrester	Apr. 21, 1953
D. 179,566	Haggar	Jan. 22, 1957